INTERNAL COMBUSTION ENGINE

Olan A. Kunz, Santa Rosa, Calif.

Application February 12, 1941, Serial No. 378,625

2 Claims. (Cl. 123—51)

The present invention appertains to new and useful improvements in internal combustion engines and more particularly to the type employing aligned cylinders and double-acting pistons operative therein.

The principal object of the present invention is to provide an internal combustion engine wherein the "swash" plate principle of drive between the pistons and the utility shaft is employed in a much more efficient, smooth and positive acting manner than heretofore attained.

Another important object of the invention is to provide an engine of the character described wherein scavenging is executed automatically and under air pressure.

A further object of the present invention is to provide a "swash" plate type of drive for internal combustion engines wherein the parts are well balanced and capable of efficient lubrication at all times.

Various other objects and advantages of the invention will become apparent to the reader of the following specification.

In the drawings:

Figure 1 represents a side elevational view of the engine.

Figure 2 is a longitudinal sectional view through the engine.

Figure 3 is a longitudinal sectional view taken substantially on a line with the utility shaft.

Figure 4 is a cross sectional view taken substantially on the line 4—4 of Figure 3.

Figure 5 is a vertical sectional view taken substantially on the line 5—5 of Figure 4.

Figure 6 is a cross sectional view taken substantially on the line 6—6 of Figure 1.

Figure 7 is an elevational view of one of the counter-balancers.

Figure 8 is a sectional view taken substantially on the line 8—8 of Figure 3.

Figure 9 is a sectional view taken substantially on the same line as Figure 8, but looking in the opposite direction.

Figure 10 is a fragmentary detailed sectional view taken substantially on the line 10—10 of Figure 1.

Figure 11 is a fragmentary side elevational view of the structure shown in Figure 10.

Figure 12 is a perspective view of one of the pitmans.

Figure 13 is a fragmentary detailed sectional view through one of the pistons showing the air intake manifold removed.

Figure 14 is a fragmentary detailed sectional

view through the connecting means between one of the pitmans and the "swash" plate.

Figure 15 is a fragmentary side elevational view showing one of the pitman balls.

Figure 15a is a sectional view of a pitman ball cap.

Figure 16 is an end elevational view of one of the pistons.

Referring to the drawings wherein like numerals designate like parts, it can be seen that broadly the engine is made up of a cylinder cluster 5, end cases 6 and 7 and "swash" plate units 8 and 9 operative therein.

As can be seen in Figures 2 and 3, the cluster 5 also includes an air pressure intake manifold 10 and an exhaust manifold 11. Extending through these horizontally spaced manifolds 10 and 11 are elongated cylinders 12 in each of which operates a pair of pistons 13, 13, one at each side of a divider 14 which extends circumferentially at the inside of the cylinder and has a fuel injection jet 15 extending therethrough.

As can be seen in Figure 4, the manifold 10 consists of a shell extending around the cluster 5, the shell being made up of side walls 16 and an outside wall 17 which has a conduit 18 extending therefrom and to a suitable air pressure source.

Tubular passageways or spacers 19 extend between the side walls 16 and through these extend tie rods 20. A tube 21 extends between the side walls 16 and a utility shaft 22 extends through this tube 21.

The case 6 consists of a shell 22a having an end wall 23. This shell 22a is secured by screws 24 to a wall 25 through which the corresponding ends of the cylinders 12 extend.

In the end wall 23 is a bearing structure 26 through which the trunnion-like end portion 27 of the shaft 22 is disposed. This trunnion-like end portion 27 carries a gear 28 which may form part of a train for operating an air pump (not shown) to which the aforementioned conduit 18 is connected, and a fuel pump 29 as well as an oil pump 30. These pumps can be attached to the bottom portion of the shell 22.

The other case 7 is of similar construction, consisting of a shell 31 having an end wall 32 and being secured by bolts 33 to a wall structure 34 through which the remaining ends of the cylinders 12 protrude. This end of the shaft 22 has a trunnion-like extension 35 extending through a bearing assembly 36 in the end wall 32. Below the shell 31 is an oil pan 37 and with this the

oil pump 30 is connected by a conduit 38. From the fuel pump 29 fuel supply tubes 39 extend to the fuel injectors 15.

Each of the "swash" plate units consists in the provision of an oblique portion 40 in the shaft 22 on which is a sleeve 41. The trunnions 27 and 35 extend from a corresponding counterweight 42 having a weight *a* at one end and being keyed as at *b* each at its opposite end to the corresponding oblique portion 40 of the shaft 22.

Carried by the sleeve 41 of each "swash" plate unit is a plate 43 disposed on a plane at right angles to the sleeve 41 and on this plate 43 is a pair of vertically spaced bearings 44, 44 for receiving the vertical trunnions 45 projecting from a frame 46 circumscribing the shaft 22 at the oblique portion 40. These trunnions have oil ducts therein. Laterally extending trunnions 47 extend from the frame 46 and are journaled in bearings 48 carried by arms 49 projecting from the corresponding wall structure 25 or 34. Thus the plates 8 and 9 are mounted so that they can wabble to operate the oblique portion 40 of the shaft 22.

Each of the pistons 13 is internally formed to receive a ball end 50 of a corresponding pitman 51. The socket for the ball consists in a ribbed pocket 52 in the piston, the ribs 53 defining pockets for holding lubricant. A retaining nut 54 is provided for each socket of each piston. The remaining ends of the pitmans 51 have their ball heads 55 feeding against internally grooved cap plates 56 which, in turn, are seated in sockets in the edge portion of the corresponding "swash" plates 43 and caps 57 attached to the "swash" complete the sockets accommodating the balls 55. As can be seen in Figures 2 and 14, the balls 50 and 55 are hollow as is the shank and each ball has an opening therein so that lubricants can circulate and keep all parts properly lubricated. It is preferable that the "swash" plates 43 have an inlet 58 so that oil can enter the corresponding pitman head 55, see Figure 14.

As can be seen in Figure 13, the cylinders 12 at the intake manifold 10 are each formed with an annular row of closely spaced slots 59. It can also be seen that each cylinder 12 is provided with heat dissipating fins 60 along its portion between the manifold and that each end fin denoted by reference character 60a is somewhat deeper than the others and is preferably grooved on its outer side as at 60b to permit a portion of the corresponding manifold to fit therein. In the matter of the air pressure manifold 10 a threaded rib 61 is provided on each cylinder 12 and an internally threaded ring or nut 62 is provided on each of these threaded portions 61 to hold the manifold 10 definitely against the fin 60a.

As is shown in Figure 10, a boss 63 having a threaded opening 64 therein accommodates the corresponding fuel injector 15.

As is clearly shown in Figure 3, the shaft 12 extends through bearings 65 located in the wall structure 25 and also through bearings 66 located in the wall structure 34.

In the operation of the engine, it can be observed, that each pair of pistons 13, 13 operate in unison, moving in opposite directions. On the power stroke of these pistons force will be exerted against the "swash" plates 43 moving the corresponding portions in such a manner as to cause the sleeves 41 to exert a torque on the corresponding oblique portions 40 of the shaft 70

22 giving a part rotation to the shaft 22 which is supplemented by the power strokes of succeeding pistons. The "swash" plate executes a wabbling motion, there any time merely being a slight lateral play of the pitman 51. As each pair of pistons 13, 13 moves outwardly the manifolds 10 and 11 are uncovered and air from the conduit 70 sweeping through the manifold 10 enters the corresponding cylinder 12 and sweeps out burnt gases by way of the exhaust manifold 11 to the atmosphere if desired through conduits or outlet pipes 71 (see Figure 1).

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In an engine, a casing including inner and outer end plates, a group of cylinders having their ends passing through holes in the inner plate, a shaft passing centrally through the group with a part of the shaft passing through the center of the inner end plate, that part of the shaft extending into the casing, through the inner end plate having a short straight part and an elongated obliquely arranged portion connected with the short straight part, a substantially vertically arranged arm connected to the free end of the oblique part, a trunnion connected with the arm and journaled in the outer end portion of the casing, a weight at the free end of the arm, a sleeve rotatably arranged on the oblique part, a plate connected to the inner end of the sleeve with the plate arranged at right angles to the sleeve, socket forming members connected with the corners of the plate and extending toward the inner end plate, pistons in the cylinders, rods connected with the pistons and having spherical members at their outer ends engaging the sockets of said members, a pair of oppositely arranged arms connected with the inner end plate and extending into the casing and having journals at the free ends, a ring-shaped plate having oppositely arranged trunnions thereon engaging said journals, said ring-shaped plate surrounding that part of the shaft at the junction of the oblique part with the short straight part and said ring-shaped plate being located in the space formed by the socket forming members, a second pair of trunnions extending from the ring-shaped plate and arranged at right angles to the first pair and the plate which is connected with the sleeve having bearing parts projecting therefrom for receiving the second pair of trunnions.

2. In an engine, a pair of spaced casings each including inner and outer end plates, the space between the casings being open, a shaft having a straight central portion passing through the center of the space and through the inner end members of the casings, a group of cylinders surrounding the shaft and parallel thereto and having their ends extending through the inner end plates, a pair of pistons in each cylinder, rods connected with the pistons and extending into the casings, the central portion of the shaft having short straight portions at its ends located in the casings and oblique portions extending from the short portions located in the casings, an arm connected at one end to the outer end of each oblique portion, the arm extending at substantially right angles and having a trunnion in-

termidate its ends journaled in the outer end wall of the casing, a sleeve rotatably arranged on each oblique portion, a plate connected to the inner end of each sleeve and extending at right angles therefrom, socket forming members at the corners of each plate and the outer ends of the piston rods having spherical members thereon fitting in the sockets of said members, a ring-shaped plate in each casing and surrounding a part of the shaft which is located in the casing, a pair of oppositely arranged trunnions on the ring-shaped plate, bearings carried by the right

5 angular plate receiving said trunnions, arms extending inwardly into each casing from the inner end plate and having bearings at their free ends and a second pair of trunnions on the ring-shaped plate and arranged at right angles to the first pair, said second pair fitting in the bearings of the arms and bolts paralleling the central portion of the shaft and having their ends connected with the inner end members of the casing.
